WITNESS:

ATTORNEY

UNITED STATES PATENT OFFICE.

BLANCHE LEACH, OF RENO, NEVADA.

STOVEPIPE LOCK.

Application filed December 23, 1922. Serial No. 602,692.

To all whom it may concern:

Be it known that I, BLANCHE LEACH, a citizen of the United States, residing at Reno, in the county of Washoe and State of Nevada, have invented new and useful Improvements in Stovepipe Locks, of which the following is a specification.

The object of this invention is to produce an extremely simple, cheap and effective means for locking a stove pipe section in a chimney.

A further object is to produce a lock of this character constructed from a single piece of suitable wire or like metal, journaled in bearings in the groove at the seam of a stove pipe section and having its ends disposed at such angles that one of the same will be brought to a position to permit of the ready insertion of the section through the opening therefor in the chimney breast and thereafter turned with the opposite end so that both of the ends will be brought to contacting engagement with the inner and outer faces of the wall of the chimney breast.

To the attainment of the foregoing, and other objects which will present themselves as the nature of the invention is better understood, reference is to be had to the drawing which accompanies and which forms part of this application.

In the drawing:—

Figure 1 is a view showing the manner in which the stove pipe section provided with the improvement is inserted in the flue opening in a chimney breast.

Figure 2 is a similar view showing the arrangement of the lock when the stove pipe section is fully inserted in the opening therefor.

Figure 3 is a sectional view on the line 3—3 of Figure 1.

Figure 4 is a similar sectional view on the line 4—4 of Figure 2.

Figure 5 is a perspective view of the lock.

Referring now to the drawing in detail, the numeral 1 designates a chimney, 2 the stove pipe opening which communicates with the flue of the chimney, and 3 a stove pipe section which is designed to be received in the opening 2.

The pipe section 3 is of the usual construction, the pipe seam of which is formed with a channel 4. Bridging the groove 4 are metal straps 5, the said straps being riveted or otherwise secured to the pipe section 3. The channel and the plates 5 provide a bear-

ing for the body or shaft portion 6 of my improved lock. The lock is preferably constructed of steel wire and the body or shaft 6 thereof has one of its ends bent at a right angle therefrom, as indicated by the numeral 7. The opposite end of the shaft 6 is also bent, but at an obtuse angle, as indicated by the numeral 8. The portion 8 has its outer end bent downwardly with respect to the journaled shaft 6 and right angularly with respect to the angle portion 8. The last mentioned portion is for distinction indicated by the numeral 9, and forms what I will hereinafter refer to as the handle of the improvement.

By swinging the shaft 6 to the position illustrated in Figure 1, the angle or finger end 7 of the shaft will be disposed downwardly or in the direction of the bore of the stove pipe section 3. When the stove pipe section is fully inserted in the opening 2, the outer angle end of the shaft will contact with the chimney 1 and the handle portion is grasped to turn the shaft to the position illustrated in Figure 2, thus bringing the angle end or finger 7 upwardly into contacting engagement with the inner wall of the chimney 1, and the angle portion 8 as well as the handle 9 into contact with the outer face of the chimney 1.

It is thought that the foregoing description, when taken in connection with the drawing will fully set forth the construction and advantages of my improvement to those skilled in the art to which this invention relates.

It is to be understood that the lock being constructed of steel wire embodies an inherent resiliency so that the finger end 7 and the handle end 8 and 9 may be bent in the direction of or away from the shaft or body 6 whereby a frictional engagement of the ends of the shaft with the inner and outer faces of the chimney will be afforded even when the shaft 6 is of a greater length than that of the opening 2.

Having described the invention, I claim:—

The combination with a chimney having a pipe opening, and a pipe section to be received in said opening which has its seam formed with a channel, of a means for locking the pipe section to the chimney, comprising a shaft received in the groove of the pipe section, plates straddling the shaft and secured to the pipe section, said shaft having one end terminating with one end of the pipe section and arranged at a right angle

with respect to the longitudinal plane of the shaft, said shaft having its opposite end extended at an obtuse angle and from thence bent at a right angle to provide a handle designed for bodily turning the shaft and the first mentioned end to bring the latter in the direction of the bore of the chimney to permit of the insertion of the pipe section through the opening therein and to also per-

mit of the handle end of the shaft being 10 brought into contact with the outer face of the chimney and thereafter further turned to bring both ends of the shaft into contacting engagement with the respective inner and outer faces of the chimney. 15

In testimony whereof I affix my signature.

BLANCHE LEACH.
